UNITED STATES PATENT OFFICE.

RENÉ DESSEIGNES, OF ASNIERES, FRANCE.

DESIGN FOR A BOTTLE.

Application filed July 24, 1924. Serial No. 10,250. Term of patent 7 years.

To all whom it may concern:

Be it known that I, RENÉ DESSEIGNES, a citizen of the Republic of France, residing in the city of Asnieres, Republic of France, have invented a new, original, and ornamental Design for a Bottle, of which the following is a specification, reference being had to the accompanying drawing, forming a part thereof.

In the drawings,

I claim:

The ornamental design for a bottle substantially as shown.

RENÉ DESSEIGNES.
